UNITED STATES PATENT OFFICE.

ALBERT M. TYLER, OF ALEXANDRIA, OHIO.

GATE-LATCH.

1,071,480.

Specification of Letters Patent. Patented Aug. 26, 1913.

Application filed June 27, 1912. Serial No. 706,256.

To all whom it may concern:

Be it known that I, ALBERT M. TYLER, a citizen of the United States, residing at Alexandria, in the county of Licking and State of Ohio, have invented a new and useful Gate-Latch, of which the following is a specification.

The present invention relates to improvements in gate latches, one object of the present invention being the provision of a novel form of latch member that may be readily attached to any latch post to permit of the ready positioning of the gate and locking thereof.

A further object of the present invention is the provision of a latching means whereby when the gate is in an intermediate position, as for instance when the outer free end is raised to permit of the passage below the gate of stock that it is desired to separate from the flock or herd, may be locked in such position.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is an elevation of a gate with the present latch, both being in normal locked position. Fig. 2 is a similar view of a gate locked, when the gate assumes an intermediate position raised. Fig. 3 is a front elevation of the detachable locking device for the gate latch. Fig. 4 is a section taken on the line 5—5 of Fig. 3. Fig. 5 is a detail perspective view of one of the catches *per se*.

Referring to the drawings, the numeral 1 designates the hinge post which carries the two hinging pintles or arms 2 for the reception of the eye-bolts 3 connected to one of the hinged plates 4 of the gate 6.

In order to provide a ready means for locking the gate in normal closed position, a locking device as clearly shown in detail in Figs. 3, 4 and 5 is employed, the same consisting of a transverse strip 23 which may be wider or narrower than the width of the latch post 22, and is provided with the over-hanging strip 24, which provides a means to prevent the entrance of moisture due to rain

or snow into the working parts of the locking device. The two strips 25, when the post 22 is narrower than the length of the plates 23 are provided to properly secure the locking device to the post. A vertically disposed plate 26 of metal is connected to the plate 23 intermediate its ends and astride the aperture or socket 23' formed in such strip, and connected to the outer face of the plate 23 are the two oppositely disposed locking members 28—28', each one of which is secured at 29—29' respectively so that the hinges 27—27' will permit the proper movement of the free ends carrying the inturned hooked terminals 30—30' to normally engage the under side of the strip 26 to provide a limiting means for the outward movement of the terminals 30—30'. In order to hold the same extended, the springs 31—31' are seated in the strip 23 adjacent to the free ends of the locking devices 28—28'. By providing the hinge points 27—27', the locking devices are made more durable, than would be the case where flat springs are employed, as practically no strain is thrown upon the hinge points, the same being free to move due to the springs 31—31' and when compressed by the free outer ends of the latch 32 and when projected outwardly into latch engagement. In the inner face at the upper end of the latch post 22 is provided a recess 33 for the reception of the outer end of the latch bar 32 when the gate is in the position shown in Fig. 2. By this means the gate may be locked in such position to permit of the separation of the smaller animals from the larger ones.

The latch bar 32 is preferably constructed as shown and is provided with the elongated slot 34 with the offset notches 35, said slot being disposed to fit astride of the pin 36 carried by the two plates 11 next adjacent to the bars 10, the pivoting or swinging bail 37 being so connected to the bar 32 and one of the slats 6 as to cause said bar to assume the position shown in Fig. 1 or normally to have its outer free end engage the locking device.

When the locking bar is in the position as shown in Fig. 2, one of the notches 35 is in engagement with the pin 36, to thus lock the bar against accidental displacement, the same being true of the bar when in the position shown in Fig. 1, it being necessary to raise the inner free end of the latch bar by means of the knob or handle 38

to release the said bar for swinging movement.

What is claimed is:

1. The combination with two oppositely disposed spring actuated catches, of a latch bar carried by a swinging closure, a swinging connection for the bar intermediate its ends to permit either free end to be rocked, and co-acting means carried by the closure 10 and the inner end of the bar to lock the bar in extended position.

2. The combination with two oppositely disposed spring actuated catches, of a latch bar carried by a swinging closure, a swinging connection for the bar disposed to permit the inner end of the bar to overbalance the outer end, whereby the respective ends of the bar may be rocked, and co-acting means carried by the closure and the overbalanced end for locking the bar in extended position.

3. The combination with two oppositely disposed spring actuated catches, of a latch bar carried by a swinging closure, a swinging connection for the bar intermediate of its ends to permit either free end to be rocked, the inner end of said bar being pro-

vided with an elongated slot with a plurality of spaced notches in the upper portion thereof, and a pin carried by the closure and extending through the slot for coaction with either one of the notches to lock the bar.

4. The combination with two oppositely disposed spring actuated catches, of a latch bar carried by a swinging closure, a swinging connection for the bar disposed to permit the inner end of the bar to overbalance the outer end, whereby the respective ends of the bar may be rocked, the overbalanced end of said bar being provided with an elongated slot, the upper edge of which is provided with a plurality of spaced notches, and a pin carried by the closure and extending through the elongated slot of the bar for co-action with one of the notches at a time to lock the bar.

In testimony that I claim the foregoing as my own, I have hereto affixed my signature in the presence of two witnesses.

ALBERT M. TYLER.
